Specification for Design.

Patented Oct. 7, 1919.

Application filed May 13, 1919. Serial No. 296,935. Term of patent 3½ years.

To all whom it may concern:

Be it known that I, PAUL P. HEIN, a citizen of the United States, and a resident of the city of New York, borough of Manhattan, in the county and State of New York, have invented a new, original, and ornamental Design for a Headlight-Dimmer, of which the following is a specification, reference being had to the accompanying drawing, forming part thereof.

Figure 1 is a front elevation; and
Fig. 2 is a plan view of a headlight dimmer showing my new design.

I claim:

The ornamental design for a headlight dimmer, as shown.

PAUL P. HEIN.
